UNITED STATES PATENT OFFICE

LOTHAR A. EDERER, OF CHICAGO, ILLINOIS, ASSIGNOR TO TEMPORATOR COMPANY,
OF CHICAGO, ILLINOIS, A CORPORATION OF ILLINOIS

TRANSMITTING AND RECORDING APPARATUS AND PROCESS

Application filed December 2, 1927. Serial No. 237,325.

This invention relates to an apparatus and to a process for transmitting and recording signals. It has for one object to provide means for transmitting a definite signal and for recording the same automatically and positively in a permanent form. Another object of the invention is to provide mechanism for recording numbers, dates and times in permanent and convenient form. Other objects will appear from time to time throughout the specification and claims.

The invention is illustrated more or less diagrammatically in the accompanying drawings, wherein:

15 Figure 1 is a prospective view showing one form of the device.

Figure 2 is a vertical cross-section taken on line 2—2 of Figure 1.

20 Figure 3 is a detailed vertical section taken on line 3—3 of Figure 2 on an enlarged scale.

Figure 4 is a detailed vertical section taken on line 4—4 of Figure 2 on an enlarged scale.

Figure 5 is a horizontal section taken on line 5—5 of Figure 2.

25 Figure 6 is a transverse vertical section taken on line 6—6 of Figure 2.

Figure 7 is a transverse vertical section taken on line 7—7 of Figure 2, with parts omitted and parts broken away.

30 Figure 8 is a horizontal, fragmentary section taken on line 8—8 of Figure 2.

Figure 9 is a transverse detailed sectional view of some of the printing members taken at line 9—9 of Figure 7.

35 Figure 10 is a transverse vertical section on an enlarged scale taken on line 10—10 of Figure 8 showing the ribbon guiding parts.

Figure 11 is a detailed showing of the ratchet wheel and associated parts with parts broken away.

Figure 12 is a transverse vertical section showing the ratchet wheel and operating mechanism with parts omitted.

40 Figure 13 is a wiring diagram showing wiring for a system including two dialing or sending, and two recording stations.

Like parts are designated by like characters throughout the specification and drawings.

45 50 A is a base member which in the form here

shown, is made of sheet metal, having an integral upwardly extending back part A¹ and threaded lugs A².

It is provided with a cover housing which is formed with a generally vertical front part B and a sloping portion B¹ and a top B², and ends B⁴, B⁵. The top is removably fastened to the bottom by screws B⁶ which engage the threaded lugs A² of the bottom A.

55 Mounted upon the outside of the inclined portion B¹ of the cover is a dialing assembly which in the form shown her is generally similar to the dialing mechanisms used in telephones. It is provided with a finger stop C and rotatably mounted dial plate C¹ which

60 has perforations C². Lying beneath the dial and fastened to the housing is a numbered disc C³. The numbers of the disc are so spaced and written that they are normally in alignment with the openings C² in the dial. C⁴ is

65 a plate or washer fastened to the dial plate C¹ and provided with letters or other markings C⁵ which are in alignment with the openings C².

70 Figure 14 is a transverse vertical section taken on line 14—14 of Figure 2.

75 Figure 15 is a transverse vertical section taken on line 15—15 of Figure 2.

80 Figure 16 is a transverse vertical section taken on line 16—16 of Figure 2.

85 Figure 17 is a transverse vertical section taken on line 17—17 of Figure 2.

90 Figure 18 is a transverse vertical section taken on line 18—18 of Figure 2.

95 Figure 19 is a transverse vertical section taken on line 19—19 of Figure 2.

100 Figure 20 is a transverse vertical section taken on line 20—20 of Figure 2.

105 Figure 21 is a transverse vertical section taken on line 21—21 of Figure 2.

110 Figure 22 is a transverse vertical section taken on line 22—22 of Figure 2.

115 Figure 23 is a transverse vertical section taken on line 23—23 of Figure 2.

120 Figure 24 is a transverse vertical section taken on line 24—24 of Figure 2.

spring leaves E^1 , E^3 , E^5 , E^7 , and alternating long spring leaves E^2 , E^4 , E^6 , E^8 . E^9 and E^{10} are spring leaves normally out of contact with each other. E^{11} , E^{11} are insulating members separating the several spring members. E^{12} is a limiting member which limits the upward movement of the spring E^9 . E^{13} , E^{13} are insulating members separating the outer ends of the springs E^2 , E^4 , E^6 , E^8 . E^{14} , E^{14} are screws which serve to hold the combination switch assembly to the housing.

F is a push button mounted within the boss D^1 provided with a stem F^1 which passes through a perforation F^2 in the portion B^2 of the housing. Within the housing, and fastened to the stem F^1 is an enlargement F^3 . F^4 is a spring lying within the boss D^1 bearing at one end upon the portion B^2 of the casing and at the other end upon the push button F . Lying beneath the push button are the spring leaves F^5 , F^6 . F^7 , F^7 are insulating parts which serve to insulate the spring leaves F^5 , F^6 from each other and from the housing. F^8 , F^9 are screws by means of which the spring leaves and the insulating parts are removably mounted within the housing. F^{10} is a projection formed upon the spring leaf, F^5 and insulated from it.

G , G^1 are bracket or supporting members mounted upon the base portion A of the housing. These bracket members are provided respectively with bosses G^2 , G^3 and upwardly extending parts or lugs G^4 , G^5 respectively. The bosses G^2 , G^3 are hollow and adapted to serve as bearings for the shaft G^6 . G^7 is a sleeve removably mounted on the shaft G^6 and having preferably formed integrally with it a ratchet wheel G^8 and a segment G^9 . The segment G^9 is provided with an enlarged arcuate portion G^{10} which may carry raised numbers G^{11} and other symbols G^{12} . These numbers and symbols correspond with the numbers and symbols of the dial mechanism described above. Fixed to the portion G^{10} by means of pins G^{13} is a ring G^{14} . It is provided with teeth on a portion of its outer surface as shown particularly in Figures 6 and 12, and elsewhere it is provided with numerals G^{15} and letters G^{16} . G^{17} is an aperture formed in the casing portion B^2 above the ring G^{14} and in alignment with the numerals G^{15} . It may be provided with a lens G^{18} held in place by a frame G^{19} . Mounted in the segmental portion G^9 is an insulating member G^{20} which has a plurality of contact pins G^{21} . G^{22} , G^{23} are connecting wires which serve to join alternating contact pins. The connection of the pins is such that each alternating pin has different polarity; this is illustrated particularly in Figure 7 and in the wiring diagram Figure 13.

H is a leaf spring provided with a contact

point H^1 and adapted to contact the pins G^{21} . The spring is supported from a bracket H^2 attached to the base A .

I is a groove formed in the sleeve G^7 adapted to receive contact pins I^2 which are mounted on a fork I^1 . This fork is pivotally supported as at I^3 in a bracket I^4 . I^5 is a generally L shaped member to which the bracket I^4 is fastened and it is itself carried by a bracket member I^6 which is fastened to the back A^1 of the housing base by means of screws I^7 ; I^8 is a magnet coil having a core I^9 . It is mounted in the bracket I^6 in general opposition to the enlarged member or boss I^{10} which is fastened to the fork I^1 .

J is a member upwardly extending from the base A . It may be formed as a lug integral with the base. Attached to it is a generally L shaped member J^1 which carries a magnet coil J^2 provided with a core J^3 . J^4 is a boss or enlarged member attached to a lever J^5 which lever is pivotally mounted at J^6 in a bracket J^7 which is itself fastened to the L shaped member J^1 . Pivotally mounted at the outer or free end of the lever J^5 is a dog J^8 . J^9 is a lug extending from one end of the base portion of the dog. J^{10} is a spring fastened at one end of the lug J^9 and at the other to the bracket J^{11} which extends outwardly and is fastened at its lower end to the member J^1 . J^{12} is a stop pin fastened to the member J^{11} and adapted to limit upward movement of the lever J^5 . The spring normally holds the lever in the position shown particularly in Figure 6, thereby holding the dog J^8 out of engagement with the ratchet wheel G^8 . J^{14} is a stop pin mounted in the bracket part G^5 and adapted to limit counter-clockwise movement of the dog. J^{15} is an additional stop pin mounted also in the part G^1 and adapted to limit downward movement of the dog. When the magnet J^2 is energized, the lever J^5 is drawn in a clock-wise direction, causing the dog to engage the teeth of the ratchet wheel G^8 and turning it in a counter-clockwise direction. This movement is limited by contact of the dog with the limiting pin J^{15} . Since the ring G^{14} and the enlarged surface G^{10} attached to the segment G^9 are all mounted upon the sleeve G^7 which moves with the ratchet wheel G^8 , this assembly of parts is given motion and this motion is controlled and limited by the mechanism just described.

K is a bracket mounted upon the base A provided with a laterally bent upper portion K^1 upon which is mounted a generally L shaped member K^2 and magnet K^3 having a core K^4 . K^5 is a laterally enlarged member mounted on the lever K^6 . The lever K^6 is pivotally mounted on a pin K^7 which is itself journaled in upwardly extending lugs K^8 which in the form here shown form part of the bracket member K^9 which is fastened to the base A . K^{10} is a printing hammer or

platen member mounted upon the lever K⁶ and provided with a relatively hard rubber upper end member K¹¹. This hammer is in general alignment with the enlargement G¹⁰ of the segment G⁹. K¹² is an extension from the main lever K⁶. K¹⁵ is a lever pivotally supported by the pin K¹⁴ in the lever extension K¹². It is notched adjacent its upper end as at K¹⁶ to engage the pin K¹⁷ which is itself mounted on a pawl K¹⁸. This pawl is adapted to engage the ratchet teeth K¹⁹ which are cut in a portion of the ring G¹⁴. K²⁰ is a pivotal support for the pawl K¹⁸ and is mounted in a bracket member K²¹ fastened to the base A. K⁴⁰ is a spring attached to the pawl K¹⁸ and tending normally to hold the pawl in engagement with the teeth K¹⁹. K²² is a spring, one end of which is wrapped about the pin K¹⁴, the other end of which bears against the lever K¹⁵ tending to move it in a clock-wise direction. K²³ is a stop pin mounted on the lever portion K¹² and adapted to limit the clock-wise movement of the lever K¹⁵. In one position the notch K¹⁶ and the lever K¹⁵ engage the pin K¹⁷ of the dog K¹⁸. This position of engagement is shown in Figures 2 and 6. K²⁴ is a leaf spring which is mounted beneath the lever K⁶, and normally holds it upward in the position shown in Figure 2. When the magnet K³ is energized, it raises the right end of the lever K⁶ as shown in Figure 2 and correspondingly moves down the portion K¹² of the lever. This downward movement is limited by the lug K³⁰ which as here shown is formed integrally with the base portion A. When the lever K⁶, K¹² is moved so as to draw downward the end K¹² the lever K¹⁵ moves with it and since it is in engagement with the pin K¹⁷ on the pawl K¹⁸, it moves the latter out of engagement with the ratchet teeth K¹⁹ on the ring G¹⁴. This movement is shown in dotted lines in Figure 12. When the dog K¹⁸ is moved out of engagement with the ratchet teeth, the ring G¹⁴ is then free to move and the spring G²⁵ which is wound by the shaft G⁶ thereupon rotates the ring G¹⁴ and the segment G⁹ in the direction indicated by the arrows in Figure 12. One of the pins K²⁵ in the ring G¹⁴ strikes the curved upper surface K²⁶ of the lever K¹⁵, and tends to move the boss into the position shown in full lines in Figure 12, thus causing the dog to return to its normal position in engagement with the ratchet teeth K¹⁹. The movement of the lever K¹⁵ in response to rotation of the ring G¹⁴ and contact with the pin K²⁵ is limited by a stop member K²⁷ which is mounted on the lever portion K¹². Attached to, and in this case, formed integrally with, the lever K⁶, is an upwardly projecting lug K²⁸ upon which is pivotally mounted a pawl L. A spring L¹ fastened at one end to the pawl and at the other end to the lever portion K⁶ holds the pawl normally in en-

gagement with the ratchet wheel L². This wheel L² is carried upon a shaft L³ which is mounted for rotation within varying members L⁴, L⁵ which are themselves secured to the base portion A. The shaft L³ carries also a feed roller L⁶ which is adapted to feed a paper tape M or any other suitable impression receiving element. A printing ribbon M¹ is also fed and moved along by the feed roller L⁶. M² is a friction roller mounted for rotation between arms M³ which are pivotally supported on a shaft or pin M⁴ threaded into a lug M⁵ formed on the bearing member L⁵. A spring M⁶ is normally used to force the roller M² yieldingly against the roller L⁶.

M⁸ is a feed roll upon which the paper tape M is positioned and from which it is fed. The roll M⁸ is mounted for rotation upon a shaft M⁹ which is supported in a bracket member M¹⁰ attached to the base A. A spring clip M¹² is adapted to fit within a slot M¹⁴ formed in the shaft M⁹.

The printing ribbon M¹ is mounted about a series of rollers N, N¹, N², N³. The roller N is mounted upon a lug M¹⁵ formed integrally as part of the bracket L⁶. The ribbon M¹ is preferably formed in a loop pass about the rollers above mentioned, in line and in contact with the paper tape, between the feed roller L⁶, and the friction roller M², and is fed forward by the feed roller L⁶. The printing tape M¹ further passing from between the rollers L⁶, M² is fed into a guiding strip O which is provided intermediate its ends with cut-away portions to permit printing. The guide O is mounted at one end upon a bracket O¹ which is secured to the bracket member L⁵. O² is a supporting member on the bracket G which serves to support the opposite end of the guide O. At the outside of this large end of the guide is a knife blade O³ which is preferably positioned above the guide. The knife blade lies within and extends through a slot O⁴ in the casing wall. The paper tape may be torn or cut across this knife blade.

P, P¹ are brackets fastened to the base A and carrying a shaft P². Mounted for rotation upon this shaft are sleeves P³, P⁴, P⁵. P⁶ is a spur gear mounted at one end of the shaft P² and P⁷ is a printing wheel having raised numerals P⁸, preferably from 1 to 10, mounted at the opposite end of the shaft P². These numerals for some purposes may be used to designate tenths of an hour. Mounted upon the sleeve P³ at the end adjacent the gear P⁶ is a gear P⁹. Mounted at the opposite end of the sleeve is a wheel P¹⁰ having upon it a plurality of numerals P¹¹ adapted to indicate the working hours. Mounted upon the sleeve P⁴ adjacent the gear P⁹ is a gear P¹². P¹⁴ is a printing wheel carrying numerals P¹⁵ numbering from 1 to 31 adapted to indicate the days of the month. Mounted on the sleeve P⁵ adjacent to the gear P¹² is a gear P¹⁶. Mounted also on this sleeve is a

wheel P^{17} carrying letters P^{18} adapted to indicate the names of the months. Enmeshed with the gear P^9 is a gear P^{20} which is mounted upon a sleeve P^{21} mounted for rotation in a bearing member P^{19} which is preferably formed integrally with the bracket P . The sleeve P^{21} extends through an aperture P^{30} in the wall of the housing and is rotated by a time clock which is not here shown, as its 10 tails form no particular part of the present invention, and this sleeve might be driven by any suitable means.

Enmeshed with the gear P^9 is a driving gear P^{22} which is mounted upon a sleeve P^{23} which is itself positioned within the sleeve P^{21} and is also driven by a time clock mechanism which is not shown. In engagement with the gear P^{12} is a gear P^{24} which is mounted upon a sleeve P^{25} lying within the sleeve P^{23} . This sleeve may be rotated by hand or by any suitable driving mechanism. Enmeshed with the gear P^{16} is a gear P^{26} mounted on a shaft P^{27} which lies within the sleeve P^{25} and has one end mounted for rotation in a lug P^{31} , which preferably is made integrally with the bracket P^1 . This shaft may be driven by hand or by mechanical means not here shown.

Beneath the printing wheels P^7 , P^{10} , P^{14} , P^{17} , is a printing hammer or platen R . It is pivoted at this upper or contact end with a rubber portion R^1 and is mounted upon a lever arm R^2 which is supported upon a pin or shaft R^3 in a bracket R^4 . R^5 , R^6 are guiding lugs adapted to hold the lever R^2 in proper alignment. The bracket R^4 is fastened to a generally L shaped member R^6 which is itself supported from the bracket R^7 which is fastened to the housing wall. The member R^6 supports a magnet coil R^8 which is provided with a core R^9 . R^{10} is a laterally enlarged member upon the lever R^2 . The parts are normally held in the position shown in Figure 7 by means of a lug R^{12} , fastened to the base A which extends upwardly and limits downward movement of the lever R^2 .

S is a bracket fastened to the base portion A extending upwardly therefrom and carrying a generally L shaped member S^1 . Supported in this member is a relay coil S^2 . S^3 is a switch lever provided with ears S^4 pivotally mounted upon the member S^1 by a pin S^5 . In contact with the side S^6 of the switch lever S^3 is a contact spring S^8 carrying insulating washers S^9 and supported upon insulating blocks S^{10} on the member S^1 . Opposite the member S^8 and normally out of contact with it is the contact spring S^{12} .

It is evident that while I have shown and described a practical working embodiment of my invention, many changes might be made in proportion, size and relation of parts without departing from the spirit of my invention, and I wish my description

and drawings therefore to be taken as in a broad sense diagrammatic, and not as limiting me to the specific forms described and shown.

The use and operation of my invention 70 are as follows.

The use and operation may best be followed from an examination of Figure 13 which is a wiring diagram. As shown in that figure there are two stations designated generally by the letters X and Y . The operation of transmission between the two is

as follows: Assuming that the operator at station X wishes to send a message to the central station Y , he first pushes down the

starting button D^2 thereby bringing the spring leaves E^2 and E^3 and leaves E^6 and E^7 into contact with each other. This closes

the spring leaves E^9 and E^{10} and establishes a circuit from the battery a through the wires a^1 a^2 and the spring leaves E^9 E^{10} and wire a^3 to the time printing magnet R^8 through the wires a^4 a^5 back to the battery. The operator then dials, for example number 9 on

the indexing unit which is designated on the wiring diagram as X^2 while still pressing down the starting button D^2 . By rotating

the dialing disc in a clock-wise direction, the lever X^5 moves out of contact with lever X^6 , and allowing the spring levers X^8 X^7 to

come into contact. The dialing disc is then allowed to return to its starting or at rest position and the cam X^8 is thus rotated and closes the spring leaves X^9 X^{10} . This takes

place as often as the number dialed. When this action takes place a contact is made and a circuit established from the battery a through the wires a^1 a^2 b , spring leaves E^2

and E^3 , the spring leaves X^9 X^{10} of the indexing dial X^2 through the spring leaves E^7 and E^6 , the wire b^1 and the paper feed magnet k^3 of the substation X , thence through the wire b^2 a^5 back to the battery. Another

circuit is established from the battery a through the wire a^1 and b , the spring leaves E^2 , E^3 , leaves X^9 X^{10} and spring leaves E^6

E^7 through the wires b^1 b^4 and the paper feed magnet k^3 of the central station Y , the wires b^5 a^5 back to the battery.

The operation of the dial is continued after the pressure is released from the starting button. The turning of the dial closes a circuit from the battery a through the wires a^1 a^2 and b , the spring leaves E^2 E^1 contact springs X^6 , X^7 , spring leaves E^5 , E^6 , the wire b^1 , the paper feed magnet k^3 , wires b^2 a^5 back to the battery. Another circuit

from the wire b^1 through the wire b^4 , paper feed magnet k^3 of the central station Y , the wires b^5 a^5 back to the battery.

Rotation of the cam X^8 closes a circuit from the battery a through the wires a^1 c , contact pins k^1 upon the segment G^9 , spring leave k^4 , wire c^1 , relay magnet s^2 , wire c^2 ,

spring leave E^8 and E^7 , contact springs X^9 , 130

X¹⁰ of the dial X², the spring leaves E⁴, E³, wire c³, spring leave H, contact pins k⁵, wires c⁴ and a⁵ back to the battery. Another circuit is established from the battery a through 5 the wires a¹, c, the contact pins k¹ and the leaf spring k⁴, the wires c¹ c⁶, relay magnet S² of the central station Y. The wires c⁶, c², the spring leaves E⁸ and E⁷, contact springs X⁹ and X¹⁰, spring leaves E³ and 10 E⁴, wires c³, spring leave H, contact pins k⁵, wires c⁴ and a⁵ back to the battery.

The magnetizing of the relay magnets S² 15 s² causes the attached spring leaves to close and thereby establishes a circuit from the battery a through the wires a¹, d, printing wheel magnet j², the wire d¹ the spring leaves s⁸, s¹², wires d², b² a⁵ and back to the battery.

Another circuit is established from the 20 battery a through the wire d⁶ spring leaves S⁸, S¹², wire d⁷ printing wheel magnet J² of the central station Y, thence through the wires d⁸ a⁵ and back to the battery.

The operation of the circuits above 25 described is used when it is desired to print numerals, that is to say, to transmit numerals and it will be understood that in the operation as above described, a message is sent from the sub station X to the central station 30 Y and in normal operation at each station the message is printed and a record is thus made of the message sent.

If it is desired to send letters instead of 35 numerals this may be done by pressing the shift button F of the substation and thereby a circuit is closed from the battery a through the wires a¹ f, switch leaves f¹, f², wire f³, the shift magnet i¹⁰, the wires f⁴, d², b², a³ and back to the battery. Another circuit is 40 made from the battery a through the wires a¹ f, switch leaves f¹, f², wire f³, shift magnet I¹⁰ of the central station Y through the wires f⁷, a⁵ back to the battery.

It will be understood that in the two 45 stations, that is the one designated as the sub station and the one designated as the central station, the sending and recording mechanisms are normally identical and thus a message may be sent in either direction 50 where, for example, the apparatus is installed in a factory, a central station is in the office, sub stations may be established at a variety of places throughout the factory, for example, at several different machines in 55 the factory. The operator of the machine desiring supplies or mechanical assistance, for example, will operate his sub-station and his message will be recorded at his sub station, the hour, time and date being automatically recorded and his message being at the same time recorded in conjunction with the date and time stamped. At the same time that this record is made at his sub-station an identical message and record is produced at 60 the main station so that there is at the office

information of what he wants and a record of the fact that he asked for it with the time of receipt of his message.

It will be understood that while I have 70 shown printing and indicating mechanism of a particular sort in my drawings, still many other types of printing mechanisms might be used and for some purposes it is desirable to use record making mechanism which employs no ink; one such form is that in which increments, letters or other stamps are impressed upon the paper and create in effect an embossing.

It will be noticed that in each dialing assembly, alternating contact points such as K¹ and G²¹, as shown in Figure 13, are of 80 different polarity. This is done as a precaution so that if for any reason the parts do not move in harmony, one of the circuits will 85 go dead and it will be necessary to commence dialing from the beginning again.

The segment G⁹ may be referred to as a 90 commutation type switch and it will be noted that the segments are so related mechanically that they move in unison and the wiring circuits are so disposed that when the circuit is closed on one of the commutation switches through positive battery, it is closed on the other switch through negative battery and vice-versa; and as the switches move from 95 point to point in unison, each switch steps from positive to negative and vice-versa. If for any reason the commutation switches get out of step and we have both switches on positive or both on negative, immediately 100 the apparatus controlled by the switches ties up and refuses to function, thereby preventing improper operation.

It will be further noted that the transmission of signals between the two systems is 105 effected by a continuous series of impulses as distinguished from interrupted impulses or from intermittent impulses.

Discrimination between signals is effected 110 by the numerical number in a series of impulses. For instance, the impulse used in transmitting signals in my apparatus comprises a series of opening and closing of the circuit. An impulse consists, for instance, of a closing of the circuit for $\frac{7}{10}$ of a second and an opening for $\frac{3}{10}$. To transmit the letter "C" for instance, three impulses will be given, taking $\frac{3}{10}$ of a second because each impulse lasts $\frac{1}{10}$ of a second. During each 115 of these impulses the circuit will be closed 7/100 of a second and open 3/100 of a second. These are nominal values selected for example only.

I claim:

1. In combination, message sending, recording and receiving stations, including an 120 automatic machine switching assembly of the dial type, arranged to signal numbers and letters, and tape mechanism at a sending and receiving station, and means at each station 130

for simultaneously making an identical impression upon each tape in response to manipulation of the dialing mechanism.

2. In combination, message sending, recording and receiving stations, including an automatic machine, switching assembly of the dial type, arranged to signal numbers and letters, and tape mechanism at a sending and receiving station, and means at each station

10 for simultaneously making an identical impression upon each tape in response to manipulation of the dial mechanism, a sending mechanism being located at each station and each station being arranged so that a

15 message may be sent from either to the other.

3. In combination, message sending, recording and receiving stations, including an automatic machine switching assembly of the dial type, arranged to signal numbers

20 and letters, and means adapted to transmit regular timed character selecting impulses of alternate polarity, and tape mechanism at a sending and receiving station, and means at each station for simultaneously making an

25 identical impression upon each tape in response to manipulation of the dialing mechanism.

4. In combination, message sending, recording and receiving stations, including an

30 automatic machine switching assembly of the dial type, arranged to signal numbers and letters, and means adapted to transmit regular timed character selecting impulses of alternate polarity, synchronized between

35 sender and receiver, and tape mechanism at a sending and receiving station, and means at each station for simultaneously making an identical impression upon each tape in response to manipulation of the dialing

40 mechanism.

Signed at Chicago, county of Cook and State of Illinois, this 28th day of November 1927.

LOTHAR A. EDERER.
